Letters Patent No. 2058 Dated May 9, 1865.

Design for a Stove.

The schedule referred to in these Letters Patent and making part of the same.

Small where it may concern:

Be it known that, Benjamin F. Johnson, of the City of Troy, in the County of Rensselaer and State of New York, have invented and produced a new and useful ornamental design for a Stove, and I do hereby declare that the following is a full and exact description of the same, referred to as is made to the accompanying photographs, in which fig. 1 is a front view, and fig. 2 is a side view of a cooking stove having an said ornamental design, and fig. 3 is a photograph of one of the doors of the same stove, like parts being marked by the same letters in all the figures.

This ornamental design for a stove can be distinguished from all others by having

First. A series of upright, parallel grooves A, shaped, arranged and cast in or on a plate or plates so as to present an appearance like that shown in the aforesaid photographs.

Second. Horizontal straps or bars B, B, shaped, arranged and cast on a plate so as to appear as represented in the aforesaid photographs.

Third. A latch C, shaped, arranged, and cast on a door so as to appear as shown in figs. 1 and 3 of the aforesaid photographs.

Fourth strap hinge A shaped, arranged and cast in a door having a grooved surface so as to appear as represented in figs. 2 and 3 of the aforesaid photographs.

Having thus described the characteristics of my new ornamental design for a store, what I claim as my invention or protection and desire to secure is set forth in the following:

The above described ornamental design in its

In testimony whereof I have hereunto set my hand this
